UNITED STATES PATENT OFFICE.

SIMEON O'NEAL, OF LUBBOCK, TEXAS, ASSIGNOR OF ONE-HALF TO WALTER F. SCHENCK,
OF LUBBOCK, TEXAS.

DUSTLESS TROUSERS-CABINET.

1,219,854.

Specification of Letters Patent. Patented Mar. 20, 1917.

Application filed June 2, 1915. Serial No. 31,718.

To all whom it may concern:

Be it known that I, SIMEON O'NEAL, a citizen of the United States, residing at Lubbock, in the county of Lubbock and State of Texas, have invented certain new and useful Improvements in Dustless Trouser-Cabinets; and I do hereby declare the following to be a full, clear, and exact description of the invention, such as will enable others skilled in the art to which it appertains to make and use the same.

The invention relates to a dustless trouser cabinet.

The object of the present invention is to improve the construction of display cabinets and to provide a simple, practical, and comparatively inexpensive dustless trouser display cabinet for displaying trousers and various other merchandise in stores for sale and adapted to keep such articles free from dust and capable of advantageously displaying a large number of pairs of trousers and of enabling the same to be readily inspected without mussing the trousers.

With these and other objects in view the invention consists in the construction and novel combination and arrangement of parts hereinafter fully described, illustrated in the accompanying drawings and pointed out in the claims hereto appended, it being understood that various changes in the form, proportion and minor details of construction may be resorted to without departing from the spirit or sacrificing any of the advantages of the invention.

In the drawings

Figure 1 is a side elevation of a dustless trouser cabinet constructed in accordance with this invention,

Fig. 2 is a vertical sectional view of the same,

Fig. 3 is a horizontal sectional view on the line 3—3 of Fig. 2,

Fig. 4 is a detail view of the trousers clamp,

Fig. 5 is a detail view of the upper bearing.

Like numerals of reference designate corresponding parts in all the figures of the drawings.

In the accompanying drawing in which is illustrated the preferred embodiment of the

dustless trouser cabinet comprising in its construction a central vertical standard 1 constructed of suitable material and mounted at its lower portion in a base 2 which is provided with roller casters 3 or the like to enable the dustless trouser cabinet to be readily moved over a floor or other supporting surface. The base which is preferably circular is provided with braces 4 consisting of webs extending radially from the central portion of the base and adapted to firmly brace the standard 1 in its vertical position. The standard 1 is provided with a tapered upper end 5 to form a pivot or journal for a horizontal top 6 which is provided at its under side with a bearing plate 7 having a central bearing recess 8 and diametrically arranged arms 9 pierced by screws or other suitable fastening devices for securing the bearing plate to the top 6 of the cabinet.

The top 6 which is preferably of polygonal form has straight marginal edges 9^a 75 which are arranged in flush relation with the upper end of inclined upwardly tapered doors 10 which are hinged to inclined strips or bars 11.

The bars 11 which are suitably secured at their upper ends to the lower face of the top 6 are supported near their centers by arms 12 having outer attaching portions 13 and provided at their inner ends with eyes 14 which receive a horizontally disposed polygonal frame 15 constructed of rod metal or other suitable material and extending around the cabinet at a point midway between the top and bottom thereof. The outer attaching portions 13 are secured by suitable fastening devices to the inclined bars or strips and the doors which are hinged at one edge at 16 and provided at the opposite edge with a suitable lock or fastening device, are preferably equipped with mirrors 17 but the doors may be of any other desired construction and they form the walls of an upwardly tapered polygonal cabinet as clearly shown in Fig. 1 of the drawings. The horizontal ring or frame 10 15 is composed of a series of angularly disposed portions 18 connected by short portions 19 and arranged in substantial parallelism with the doors of the cabinet and con-

stituting supports or stops for inclined sections or trouser supports 20 consisting of upwardly tapered boards connected at their upper ends with the top 6 by hinges 21 having links 22 extending downwardly and inwardly from the top 6 and offsetting the upper ends of the trouser receiving sections or supports 20 from the outer edges of the top 6 as clearly shown in Fig. 2 of the drawing. The links 22 have attaching portions 23 which are secured to the inner or rear faces of the trouser receiving sections 20. The trouser receiving sections normally rest against the horizontal frame or ring 15 and the latter is supported by inclined braces 24 provided at their upper ends with eyes 25 to receive the ring or frame 15 and having angularly bent vertically disposed lower terminals 26 which engage sockets or 20 openings 27 of a collar 28 mounted for rotary movement on the lower portion of the standard 1 and arranged upon a shoulder 29. The collar 28 is adapted to rotate on the standard to enable the cabinet to be 25 turned in either direction for displaying any of its contents.

The trouser receiving supports or sections which are provided at their lower ends with handles or loops 30 are equipped at their 30 upper ends with trouser clamps consisting of rock shafts 31 journaled in suitable bearings 32 and 33 and provided with crank bends 34 carrying clamping plates 35. The clamping plates 35 which are provided with 35 eyes 36 to receive the crank bends present relatively broad flat faces to the trousers and are adapted to engage the same without creasing the trousers. The rock shaft is constructed of resilient material and the 40 crank bend operates as a resilient or spring portion and is adapted to be placed under tension by a hand wheel 37 or other suitable operating means and the said rock shaft is secured in its adjustment by means of a 45 ratchet wheel 38 and a spring actuated pawl 39. The ratchet wheel is suitably fixed to the shaft and the pawl which is pivotally mounted at a point intermediate of its ends on the bearing 33 is yieldably maintained in 50 engaged position with the ratchet wheel by a coiled spring 40. The trouser receiving sections are adapted to be swung upwardly to a horizontal position to facilitate arranging a number of trousers on the sections and 55 they are supported in such horizontal position by braces 41 constructed of rod metal or other suitable material and composed of upwardly diverging side portions 42 and a central lower stem 43 provided with a shoulder 44 adapted to engage the ring or frame 15 and preferably formed by a projecting hook shaped lug. The upwardly diverging sides 42 are provided at their upper ends with eyes 45 which are linked into suitable

eyes projecting from the inner or rear faces 65 of the trouser receiving sections.

It will be seen that the trouser cabinet is exceedingly simple and inexpensive in construction, that it is adapted to contain a large number of trousers or various other 70 articles of merchandise and that it is capable of advantageously displaying the same and of keeping its contents free from dust.

The cabinet may be constructed of various sizes and may be provided with any desired 75 number of doors and hinged supporting sections.

Furthermore, it will be apparent that the top 6 and the mirror doors constitute an ornamental casing which is easily rotated on 80 the standard to afford ready access to any portion of the cabinet.

What is claimed is:—

1. A cabinet of the class described including a standard, a casing mounted for rotary 85 movement on the standard and provided with door openings and having doors, hinged sections carried by the casing and located in rear of the doors and adapted to swing outwardly from the casing through 90 the door openings to carry trousers placed thereon entirely beyond the casing, an open frame or ring extending around the interior of the casing, inclined braces supporting the open frame or ring and connected at 95 their lower ends with the standard and mounted for rotary movement to permit the frame to revolve with the casing, and means carried by the sections for engaging the open frame to support the sections in an ex- 100 tended position.

2. A display cabinet of the class described comprising a standard, a top mounted for rotary movement on the standard, an open frame or ring surrounding the standard 105 and also mounted for rotary movement, inclined bars secured at their upper ends to the top and spaced apart to form door openings, arms connecting the inclined bars with the said ring doors hinged to the bars and 110 forming the walls of the cabinet, sections hinged to and depending from the top of the cabinet and arranged to swing outwardly through the door openings to carry the trousers entirely outside of the cabinet 115 and means for supporting the sections in such extended position, said means engaging the ring or open frame.

3. A display cabinet of the class described comprising a standard, a top mounted for 120 rotary movement on the standard, an open frame or ring surrounding the standard and also mounted for rotary movement, bars secured at their upper ends to the top and spaced apart to form door openings and connected at points intermediate of their ends with said ring or frame, doors hinged to the 125 bars, trouser receiving sections hinged to the

top and adapted to rest against the frame or ring and also arranged to swing outwardly through the door openings to carry the trousers outside of the cabinet and means for supporting the sections in their extended positions, said means engaging the opening frame or ring.

In testimony whereof I affix my signature in presence of two witnesses.

SIMEON O'NEAL.
